[57]

ABSTRACT

This invention pertains to the performance of a microroutine in accordance with a program being run on a processor having user's instructions in main memory. External devices having discrete device numbers cause interrupt signals to be transmitted to the microroutine which acknowledges the interrupt signal and obtains the device number associated with the signal. A service pointer is fetched from the service pointer table in the main memory corresponding to the device number, which in turn defines a service block function to be fetched from the main memory. Input - output service is then performed for the external devices in accordance with the interrupt service block function without interrupting the program that is being currently run.

**PROCESSOR SERVICING EXTERNAL DEVICES, REAL
AND SIMULATED**

BACKGROUND OF THE INVENTION

A. Field of the Invention

This invention relates to the field of art of general purpose digital processors performing microinstructions.

B. Prior Art

In the field of relatively small scale processors, microprograms have been used to provide a high degree of flexibility and economy. By using microprogramming incorporated in a read only memory (ROM), the processor computation time for a set of specific operations may be significantly decreased. However, a significant problem with such microprogrammed processors has been in their limitation in real - time response. Specifically, in prior processors, there has been one core location reserved for exchanging program status words (PSW) when an external attention came in. At this time, the processor is required to generate an interrupt and use software to acknowledge the interrupt and then identify the device and take the necessary action. This operation has been relatively time consuming and utilized a large amount of core memory for the extra routines and for device tables.

SUMMARY OF THE INVENTION

A system and method for performing a microroutine with respect to a program being run on a processor having user's instructions in main memory. External devices (or the processor simulating external devices) cause interrupt signals to be generated having discrete device numbers. The system acknowledges the interrupt signals in accordance with the user's instructions and performs programmed instructions of the microroutine after acknowledging the interrupt signals without interrupting a currently running program. The microroutine being run is contained in a read only memory separate and distinct from the processor main memory.

BRIEF DESCRIPTION OF THE DRAWINGS

FIGS. 1A - B taken together illustrate in block diagram form a general digital processor for performing microinstructions in accordance with the invention;

FIG. 2 illustrates a flow chart for the four phases of the processor of FIG. 1;

FIG. 3 illustrates in block diagram form more detail of the decode read only memory of FIG. 1;

FIGS. 4A - B taken together illustrate in block diagram form the interrupt service block and interrupt service block function codes;

FIG. 5A shows in block diagram form the activate sequence through which an interrupt signal is sent through a simulated device or from some external devices;

FIGS. 5B₁ - B₂ taken together illustrate the data transfer sequence to either a done phase or a termination phase;

FIG. 5C illustrates in block diagram form the sequence detailing the ability to count interrupts for pulse counting operations; and

FIG. 5D illustrates in block diagram form the termination and done sequences for the external device interrupt signals.

DEFINITIONS

Microinstruction — hardware level instruction which causes a specific machine operation to occur.

Microprogram — a collection of microinstructions which causes a specific user instruction or other functions to be executed.

Microroutine — a functional segment of a microprogram.

User instruction — an instruction by the programmer which is placed in core memory.

Interrupt — an instruction to stop running program, save the status of that program, exchange program status word (PSW) to branch to a new program designed to service that interrupt, and execute the new program.

Attention — an external interrupt signal which is a request from a peripheral device for processor service.

Microoperations — there are ten basic kinds of microoperations which are combined in the microprogram to cause the hardware to take those steps necessary at the hardware level to perform user instructions. These microoperations may be any one of the following:

10	A	Add L	Load
	S	Subtract C	Command
	X	Exclusive OR T	Test
	N	AND B	Branch on Condition
	O	Inclusive OR D	Decode

15 **Formats** - there are four possible formats and the ten microoperations fall into any one of four of these formats:

Register to Register Format

Add, Subtract, Exclusive OR,

AND, Inclusive OR, and Load

RD Register 34

25	0	3 4	7 8	11 12	15
	OP-Code	D	S	E	

30 **D** = Destination field: the result of the operation is placed into the register whose address is in this field.
S = Source field: the address of the register containing the second operand is in this field. The first operand comes from the A Register (AR).
E = Extended operation field: specifies options within the operation.

IMMEDIATE FORMAT

Add Immediate, Subtract Immediate,

Exclusive OR Immediate, AND Immediate,

Inclusive OR Immediate, and Load Immediate.

Register 34

0	3 4	7 8	15
OP-Code	D	Data	

50 **D** = Destination field: the result of the operation is placed into the register whose address is in this field.
DATA = the second operand is in this field. The first operand comes from the A Register (AR).

TEST AND COMMAND FORMAT

Register 34

60	0	3 4	15
OP-Code		TC-Code	

65 **TC Code** = Test or Command Code. Specifies the signal to be tested, or specifies the command to be performed.

BRANCH ON CONDITION FORMAT

Register 34

75	0	3 4 5 6 7 8	15
OP-Code	C V G L	Address	

C = Carry
 V = Overflow
 G = Greater than zero
 L = Less than zero

ADDRESS = if any specified condition (C, V, G, or L is met, the program is transferred to the 8-bit address specified by this field.

DESCRIPTION OF THE PROCESSOR 10 HARDWARE OF FIGS. 1A-B

Referring now to FIGS. 1A-B there is shown a general purpose digital processor 10 designed to perform microinstructions. These microinstructions are programmed into subroutines that are permanently wired so that the read out can not be changed by the program. Combinations of subroutines perform the more complex operations that make up each of the user's instructions. There are certain functions that must be performed regardless of the user's instruction to be done. Namely that instruction must be fetched from a core memory 25, decoded and then executed. Processor 10 comprises 16, 16 bit general registers 14, an arithmetic logic unit (ALU) 16, and instruction register (IR) 17, read only memory 20, a decoder read only memory (DROM) 21, an input-output system 24, a core memory 25, a set of microregisters 15, control logic 23 and a display system 27. The foregoing main systems of processor 10 are connected between S and B busses 30 and 31 respectively by way of ALU 16 in conventional manner.

The operation of processor 10 basically centers around ROM 20 which contains the microprogram and which directs all of the operations within processor 10. The ROM locations are addressed by a 12 bit register RA 20a. Information read from ROM 20 is placed in a 16-bit data register (RD) 34. Bits 0-3 of RD 34 specify a microoperation to be performed which in turn defines the meaning of the remaining 12 bits. The microprogram is prewired in ROM 20 by weaving wires through transformers. The microinstructions read from ROM 20 direct processor 10 by way of processor control unit 23. Unit 23, may, depending on the microcode, set up the ALU 16 to a desired mode of operation, test for specified hardware conditions, issue functional commands to establish hardware conditions, initiate memory cycles, set up microprogram loops or load and unload selected registers in the hardware register stacks 14 and 15. An explanation of a typical processor control 23 performing the functions listed herein is detailed in GE-635 Systems Manual, pages III-1 to III-10 and IV-2 to IV-7.

There are five general purpose microregisters 15a-e labeled M0-MR each of which has a capacity of 16 bits and is directly addressable from RD 34. Registers 15a-e are general purpose registers and may be used for differing purposes by the microprogram. However, program status word (PSW) register 15f is a 16 bit register which has a specific use in processor 10. The microprogram must use register 15f as well as registers 15g-h in a specific manner. Register 15f indicates the system status relative to the user program being executed. Bits 0-11 of register 15f define machine status. Bits 12-15 are set apart in a condition code register (15j) which may be loaded only from a flag register 15i. When register 15f is loaded, bits 12-15 of bus 30 are loaded into register 15i instead of register 15j. This propagates user status from the user level to the microlevel at which the hardware operates. FLR register 15i and ultimately register 15j reflect the results of the microinstruction, or instructions in the case of a user microroutine, just performed.

The location counter (LOC) 15h is a 16-bit appendum to register 15f which holds the address of the next user instruction to be performed. Register 15h is directly addressable by register 34. However, register 15h may be forceably selected, regardless of register 34 in the decode microinstruction, later to be described.

A memory address register (MAR) 15g is a 16-bit register used to address locations in core memory 25. Register 15g ap-

pears twice, once on the interface to core memory 25 and once in processor registers 15. Loaded into core memory 25 are the functions shown for interrupt service block (ISB) of FIGS. 4A and ISB function code of FIG. 4B.

- 5 A memory data register 35 is a 16-bit register used to hold data read from or written into core memory 25. Register 35 is directly addressable by register 34. Register 35 is separated into two bytes (MDH)register 35a and MDL register 35b which may be loaded separately on cross shift operations.
- 10 IR register 17 is a 16-bit register used to hold the user's instruction currently being processed. Register 17 is directly addressable by register 34. In addition, provision is made for unloading only bits 8-11 of register 17 to bits 12-15 of B bus 31 for comparison between the mask (M1) 17a field and the register 15i when executing user's branches. Bits 0-7 of register 17 (the user's operation code 17b) are used to address locations in DROM 21. The remaining 8 bits select general registers 14.
- 15 Each of the general registers 14 has a capacity of 16 bits. These user's registers (GR0-GR15) 14a-o are not directly addressable from register 34. In the prior description all registers have been directly addressed from register 34. However, the general register 14 selection is indirectly made. To access a particular register 14a-o it is necessary to address the appropriate IR 17 field which contains the address of the desired user's register 14a-o. To access the register specified by IR 17 bits 8-11, user's designation (YD) is addressed; to access the register specified by IR bits 12-15, user's source (YS) is addressed.
- 20 Specifically, an address is taken from register 34 and that address points the processor to YD or YS. The number that occurs at YD or YS is decoded to select a particular one of the general registers 14a-o. Accordingly, it is necessary that IR register 17 contain the proper address before one of the registers 14a-o is selected. DROM 21 may comprise up to a maximum of 128 prewired words each 12 bits long by means of a read only memory in which the cores are wired in the manner well known in the art.
- 25 DROM 21 is interrogated only on a decode microinstruction and the resulting 12 bit read out is loaded into RA register 20a. DROM 21 holds the starting addresses of the microroutines required to perform user's instructions. Register 20a may also be loaded with hardware generated addresses in the decode microinstruction. The most significant bit (MSB) of the DROM 21 output designates whether or not that particular user instruction is privileged. PSW bit 7, 15f, if set by the user program, enables privileged instruction (PI) to be dropped. Then if a PI is attempted with PSW 07 set, the hardware forces an internal illegal instruction interrupt by way of clearing the register 20a.
- 30 Counter register 18 is a four bit decrementing register. It may be preloaded with any number from 0 to 15 to count the number of repetitions of a single microinstruction or a block of microinstructions. This counter is used in the multiply or divide sequences to cause 16 iterations of the microinstruction sets as will later be described with respect to the multiply or divide sequences to cause 16 iterations of the microinstruction sets as will later be described with respect to the multiply or divide operation.
- 35 Arithmetic register (AR) 16a is a 16 bit register used to hold the first operand in arithmetic or logical microoperations. It is one of two direct inputs to the ALU 16. The other input to ALU 16 is the 16 bit bus 31 which receives data from any one of 29 possible sources. The two 8 bit bytes of bus 31 may also be swapped by means of cross shift logic 16b.
- 40 ALU 16 includes a 16 bit parallel adder-subtractor logic network 16c with a one-bit look ahead carry. The 16 bit arithmetic or logical result from network 16c is gated to S bus 30 which in turn is gated to one of thirty three possible designations.
- 45 Input-output transfer is accomplished by way of a single microinstruction contained in ROM 20. I/O control lines 24a
- 50
- 55
- 60
- 65
- 70
- 75

are decoded from RD bits 14 and 15 in RD register 34. Input data is taken from data request lines (DRL 0-7) 24b and placed directly on bus 31 bits 8 - 15. Output data is taken from bus 30 bits 8-15 and loaded directly to the data available lines (DAL) 0-7 (24c).

GENERAL OPERATION OF PROCESSOR 10

Processor 10 is basically oriented toward the standard user's instruction set of Interdata Inc. Reference Manual publication no. 29-004 R01, copyright 1967. The user's instruction may cause many hardware and microprogram functions to be performed before actually entering the microroutine that will execute the instruction.

The instruction set is made up of three basic classes of instructions. The first class is defined as RR which means Register-to-Register, the second class is RX which means register to indexed memory and the third class is RS which is a mixture of instruction forms. The major portion of this third class comprises immediate instructions. An immediate instruction is an instruction in which the address field is treated as the data instead of the address of the data.

In processor 10 there are four hardware conditions known as "phases" as illustrated in FIG. 2. Each phase has corresponding sets of microinstructions. In general, phase zero is dedicated to users instruction fetch and class decoding. Phase one is dedicated to indexing for the second operand. Phase two is dedicated to user's instruction execution and phase three is dedicated to interrupt service and display support. These phases affect and in turn are affected only by the decode microinstruction. Upon microcode command, the appropriate next phase is entered. The phase entered is a function of the current phase and the other machine conditions.

FIG. 2 illustrates in general form a flow chart of the hardware and microprogram functions that are common to all user's instructions. A detailed computer listing of the entire basic microprogram will later be given.

A typical execution cycle of the user instruction will now be explained. User instruction execution begins when phase zero is entered.

Prior to entering phase zero a decode instruction exiting phase two or three caused core memory 25 to be read from the location specified by the location counter 15h. At the same time the location counter was incremented by two and address register 20a was forced to the starting address of the phase zero microinstruction sequence 40. The microinstructions at location 0010-0012 are used to place the OP code in the appropriate register for examination by the hardware. Specifically, the instruction register 17 is loaded from register 35 and register 25a is loaded from register 15h. In operation, if the format of the OP code placed in register 17 indicates that the instruction is RX or RS then terminate phase zero and fetch the second half of the instruction and at the same time increment the contents of register 15h by two. If the format of the OP code placed in register 17 indicates that the instruction is RR, then terminate phase zero and enter phase two. The foregoing is the general operation of phase zero block 42.

More particularly, the decode instruction exiting phase zero makes the following hardware decisions. If the instruction OP code format is RR as determined by block 43, then exit block 43 and enter phase two. If the decision is "no", then exit block 43 and enter block 44. If the OP code is RS and is not indexed exit block 44 to block 46 and exit block 46 to phase two block 50. If the OP code is RS and has been indexed then go to phase one and to location 0004 in the microprogram to index the address field. After performing that index then exit to phase two block 50. If the OP code was not RR or RS then it must be RX so decision block 45 is entered. If indexed, then go to phase one and to address 000C in the microprogram (block 51) and index and fetch the second operand by block 53. Upon completion of this operation exit to block 50. If the OP code was RX and unindexed then go to phase one and to location 0008 in the microprogram and fetch the second operand in block 56. After that operation exit to block 50.

It will be understood that the operations performed by blocks 48, 53 and 56 are discrete instructions and can be seen at the respective addresses of blocks 47, 51 and 55 in the microprogram listing given later. The respective addresses were selected nowhere else but from the hardware by the decode instruction exiting phase zero.

A major function of digital computers is in the decoding of instructions and entry into the proper execution cycle of the processor. Usually this function has required a substantial amount of relatively expensive hardware or a time consuming logical manipulation of the OP code. In accordance with the invention an optimum cost performance ratio has been achieved by using read only memory techniques and a minimum number of logic components. In general the operation involves the fact that any time that phase two is entered either from phase zero or phase one, DROM 21 is interrogated. DROM 21 is addressed by the operation code (bits 0-7) of IR register 17. Each of the user's instructions has a unique 12 bit word that has previously been wired into DROM 21. This word is the starting address of the microroutine which will execute the specific user's instruction. The read out of DROM 21 is automatically jammed into ROM 20 address register 20a.

The hardware associated with block 50, FIG. 2 is shown in more detail in FIG. 3. For logical explanation FIG. 3 will be described before completing the description through phase two and three of FIG. 2. It will be noted that some of the blocks of FIG. 3 are the same as in FIG. 1a though slightly changed in location and form for the purpose of description in FIG. 3. The bits of the OP code from register 17 are taken by way of lines 60 to gates 62 and by way of lines 63 to gates 64. In gates 62 the OP code is used to select one of 16 X-line switches and in gates 64 the OP code is used to select one of eight Y-line switches. Gates 62 and 64 are connected to an 8 by 16 diode matrix 65. Gate 64 provides a positive current pulse on one of the eight Y-lines and gate 62 provides a ground return on one of the 16 X-lines. Each Y-line terminates with 16 individual diodes in the matrix. Word lines 67, connected between a Y-line terminating diode and an X-line, are threaded through an array of 12 transformers 68. In this manner one of 128 possible word lines 67 is pulsed. Each of the legal user's instructions is associated with an individual one of the word lines 67 in DROM 21. Accordingly, each of the word lines holds a starting address of a microroutine that will execute a specific user's instruction. Read only memories are well known in the art and are described in Development of an E-Core Read Only Memory, P.S. Sidhu, AFIPS Conference Proceedings, Vol. 27, Part 1, 1965 Fall Joint Computer Conference.

Word lines 67 are threaded through transformer 68 in a manner to provide a desired 12 bit starting address when a particular one of the word lines 67 is pulsed. The starting address generated by transformers 68, upon pulsing word lines 67, is applied by way of 12 read out amplifiers 70, one for each of transformers 68. After being amplified, the starting address is applied by way of lines 71 to RA register 20a. In this manner, the data read out from the pulsed word line 67 is applied as an address to register 20a. Thus, in accordance with the invention, the address of the user's instruction microroutine has now been placed in register 20a that will execute the desired user's instruction placed in IR register 17.

It will now be understood in accordance with the invention the housekeeping and instruction decoding work of the processor which had previously decreased the speed of the processor for specific user's instruction sets has been substantially decreased. In addition, it is now simple and inexpensive to add additional user's instructions to the user's instruction set. Specifically, for each new instruction, a microroutine is wired into ROM 20 and the starting address of that microroutine is wired into DROM 21 by adding a word line between a terminating Y-line diode and an X-line. The word line is threaded through transformer 68 in a manner to cause the 12 bit starting address to be read out. This starting address is

wired at the location whose address is the OP code of the new instruction.

Logic block 73 comprising a plurality of gates and flip-flops contains many of the logic decisions described with respect to phase zero, block 42, FIG. 2. In addition, block 73 provides the proper sequence of signals to obtain DROM read out 71 into register 20a by way of a clear line 74 followed in time by an enable signal on enable line 75. Detailed explanation of a typical logic block 73 performing the functions listed herein is detailed in R. Threadgold et al., U.S. Pat. No. 3,404,378 entitled "Computers".

The output buffer for ROM 20 is provided by RD register 34. Bits 0-3 are applied by way of lines 73a to logic block 73 and indicate that register 34 contains a decode instruction. In addition bits 12-15 are applied by way of line 73a to block 73 and define the extended operation field. With the foregoing information from lines 73a, block 73 also receives information from IR register 17 by way of lines 73b. Bits 0-3 of IR register 17 indicate what class of user's instruction is held in the IR. Bits 12-15 indicate whether or not the instruction has been indexed.

Now that the hardware associated with block 50 has been explained with respect to FIG. 3, the description will now return to FIG. 2 where it will be remembered that the phase two entry point 50 is derived from DROM 21. As previously described, DROM 21 may have up to 128 bit words wired into it and the words are addressed by the user's instruction of IR 17. DROM 21 has a word line for each instruction in the user's instruction set. Enabling DROM 21 causes the selected word line to be pulsed during the phase zero or phase one decode instruction and bit zero of DROM 21 is ANDED with bit 7 of the PSW. If the result is not true, the read out provides a starting address of a phase 2 microroutine which is placed into RA register 20a. If the result is true, the read out is set to zero and the instruction is read as illegal. This provides for privileged instructions under control of bit 7 of the PSW.

Instructions not in the user's instruction set are illegal and will not have a corresponding word line in DROM 21. When phase two is entered and a nonexistent DROM word line is pulsed, the read out, all zero's, is placed in register 20a. Location zero (0000) in ROM 20 is wired with all zero's (0000). When ROM address 0000 is read the contents are placed in RD register 34. All zero's in RD register 34 is defined as "illegal" and results in an unconditional phase three as shown by decision block 82. Thus, ROM address is forced to block 84 having address 0200 which is the entry point of the illegal instruction trap microroutine.

If the user's instruction is not illegal then user's subroutine block 88 is entered. There may be as many blocks 88 as there are user's instructions in the user's instruction set. One of these instruction sets, which will later be described in detail with reference to FIG. 4, is multiply and divide. Thus at this time the user's instruction subroutine is performed.

Regardless of the particular subroutine performed, the functions done by the decode instructions exiting block 88 are identical. Specifically, when phase two is exited at block 90 the decode microinstruction tests for interrupts. If any interrupt other than an external attention signal is true, phase three will be entered and the ROM address register 20a is loaded with address 0014, block 91. If no interrupts are pending, block 92 is entered to fetch the next user's instruction from core 25. At the same time, phase zero is entered and the ROM address in register 20a is loaded with address 0010, block 40. In this manner, there is provided means for returning to decode and execute the next user's instruction from the main core memory 25.

In phase three, block 100, microroutine sets are dedicated to display and interrupt support. The entry points to block 100 and 0014, block 91 and 0200, block 84. Block 85 results in a program status word swap after which block 93 is entered. Block 93 services any interrupt present. After successfully servicing any interrupt, block 93 is exited and block 96 is entered which examines the status of the display panel. If no operator

interrupts are pending, then enter block 95 and execute the decode instruction which fetches the next user's instruction from core memory 25 thereby to enter phase zero, block 40.

If an interrupt instruction is given by an external attention signal then the special microroutine of FIGS. 5A - 5D is entered. Referring to FIG. 5A where an external attention signal, block 140 intervenes, processor 10 enters the microroutine to service attention signal block 140. In the microroutine block 142 acknowledges the interrupt instruction. In like manner, the system may be tested by itself under program control where the system may simulate the occurrence of an interrupt signal being sent by an external device. Processor 10 sends a signal to block 260 which is a simulated interrupt signal. Exiting block 260, block 262 is entered where a device number is produced. The microroutine then enters the program directly after the program acknowledge block 142. A device number must be defined to identify an information path to direct the microroutine instructions. Once acknowledged, block 144 is entered to fetch a service pointer from a service pointer table located in core memory 25. Block 146 acknowledges the interrupt and based on the address received back from the external device, indexes through the service pointer table located in core memory 25. Block 146 inspects the value for the external device in the service pointer table and if this value is even block 146 is exited and the program enters block 148 where the routine does an immediate program status word exchange at the location indicated by the value in the service pointer table and exits to block 150. The program flows from block 146 to block 148 and finally exits at block 150 defined as the immediate interrupt. This mechanism allows for the use of 256 unique locations for exchanging program status words and identifying particular devices.

If the value fetched to block 146 from the service pointer table is odd, the routine exits block 146 and enters block 152 to pick up an interrupt service block function from the location indicated by the service pointer table. Exiting block 152, block 154 is entered to determine whether or not the interrupt service block function shown in FIGS. 4A - B is a data transfer. Where the function is found to be a data transfer block 154 is exited and block 156 is entered wherein the path of FIG. 5B is followed. Where the function is found not to be a data transfer, block 158 is entered from block 154 and the path of FIG. 5C is followed.

Where the function code indicates a data transfer in reference to FIG. 5B, the signal passes from block 150 indicating a data transfer to block 220 where the microroutine loads two of its registers with the current address and final address from the ISB, FIGS. 4A - B. Once the registers are loaded block 222 is entered where the byte count is set from the function, in sequence the external device is addressed and status received in block 224. The status is checked in block 226 and when it is found acceptable, block 228 is entered to determine whether a read or write instruction has been sent. Assuming a read instruction exists, then within block 230, the data is read and stored in the current address, the current address is incremented and the byte count is decremented.

If the byte count does not equal zero as checked in block 234, the microroutine is diverted back to block 230 to continue the read data function and decrement the byte count until it does equate to zero as verified in block 234. If the byte count does equal zero, then the current address is stored in the ISB as shown in block 246.

The microroutine then enters block 248 where the current address is compared with the final address. Where the current address is less than or equal to the final address, the flow path goes to block 250 where a check is made to determine whether the terminal character bit is set. If the terminal character bit is not set, then the microroutine goes to the DONE phase as shown by block 162. If the terminal character bit is set then block 252 is entered where the terminal character is fetched from the ISB. The terminal character is then compared with the last character and if they are not equal, then the microroutine goes to the DONE phase

represented by block 162.

Where the terminal character is equal to the last character as compared in block 254 or where the current address is greater than the final address in block 248, then the microroutine sets the function to a no operation as shown in block 240. The function is then stored in the ISB upon entering block 242. The microroutine exits block 242 and enters block 244 where the device number status is stored in the ISB. From this the microroutine goes to the termination phase as represented by block 178.

In similar fashion, where a write instruction has been sent and checked in block 228, the microroutine is then diverted to block 232 where data is written from the current address, the current address is incremented and the byte count is decremented. Within block 236, the byte count is analyzed to determine whether it is zero. When the byte count is not equal to zero, the microroutine reenters block 232 and continues to decrement the byte count until it is zero as analyzed within block 236. Once the byte count is zero, the microroutine then follows the identical path as described in the preceding paragraph with respect to the read instruction.

Returning to block 226 where the status is checked, if the status check is found not to be acceptable, then the microroutine enters block 238 where the initialized bit, the no operation bit, and the "Q" bit, which is the bit in the termination phase determining whether or not an entry is made, are set and finally the chain bit is reset. The microroutine then enters block 240 to set the function to a no operation state and follows to termination block 178 in exactly the same manner as would be found if the status check in block 226 was acceptable.

Referring to FIG. 5C where the function is determined to be a non-data transfer, the signal enters block 158 from FIG. 5A and exits to the NOP block 160 where NOP bit is either set or not. Where the indicated function is a no operation, the signal leaves block 160 and enters block 162 where the microroutine starts or continues at the next instruction as specified by the PSW. Where the NOP bit is not set, upon exiting from block 160, the signal enters block 164 where the initialize bit is either reset or not. If an initialized function is indicated, in block 164, the microroutine resets the initialized indicator within block 166 and enters block 168 to check for the output command 1. If the output command 1 is set in block 168, the microroutine signal enters address block 170 where the device is addressed and outputs the command byte from the ISB in block 172. The signal then exits to the DONE phase block 162 as indicated on FIG. 5D. If the output command within block 162 is not set, the microroutine enters block 174 to check for decrement memory and test or NULL.

Bits 2 and 3 of the function code indicate the decrement memory and test (DMT). In this operation, the count field of the ISB is decremented by one for each interrupt signal. Where the count goes to zero, the termination phase is entered. In addition, if bits 2 and 3 of the function code are both set, such indicates the NULL function wherein the termination phase is entered. If neither of those is set, the microroutine exits to C block 156 on FIG. 5B. The signal enters block 176 to check DMT. If no DMT, the bit is set and the microroutine enters termination block 178. If the function indicates a decrement memory and test found in block 176, the microroutine enters block 179 to fetch the count from the ISB, exits block 179 and enters block 180 to decrement the count by one and restore it. Block 182 checks the count and if the count is equal to zero, the program exits to the termination phase E block 178 on FIG. 5D. Where block 162 indicates a nonzero count, the program exits to the DONE phase D block 162 in FIG. 5D.

Where the initialize bit is not reset in block 164 the signal bypasses blocks 166, 168 and 174, reentering the program at the DMT block 176 and carries through the remaining instructions as described in the preceding paragraphs. It is not a decrement memory and test; it has to be a NULL and the microroutine exits to the termination phase E on FIG. 5D. The

decrement memory and test function gives one the ability to count interrupts for post current operation.

Referring now to the termination phase entrance at block 178 of FIG. 5D, the microroutine checks the queue bit in the function code of the ISB in block 184. If the queue bit is set within block 184, it sets a flag for reference in the DONE phase and the signal is directed to block 186 where the queue in the core is determined. If the queue is full, block 188 is entered where the address of the ISB is put into location 8A and 10 loads a new PSW from location 8C in block 190 finally performing a PSW exchange indicated by block 192. If the queue is not full as checked in block 186, the address of the ISB is put in the queue at block 194. The chain bit is then analyzed upon entering block 196. If the chain bit is set, the chain value from the ISB is put in the service pointer table at the location specified for this device, at block 198. The DOIT bit is then analyzed from the function code in block 200. When the DOIT bit is set, the microroutine is reentered through block 202 as shown in FIGS. 5A and 5D. As shown in FIG. 5A, the reenter phase is input to the program between blocks 144 and 146. This allows the generation of an immediate interrupt on termination of an IO transfer. Or it can allow the starting of another IO transfer to the same device using a new interrupt service block. In this manner, time saving is achieved due to the fact that it is not necessary to go into software to obtain another IO transfer.

If the chaining bit, block 196, is not set or the DOIT bit, block 200, is not set, then the DONE phase, block 162 in FIG. 5D is entered. On entering the DONE phase, the microroutine checks the queue flag in block 163. If this is reset, it is directed to exit block 150. If the queue flag is set, the microroutine is directed to block 204 where a check on bit 6 of the PSW is made. If it is reset, the microroutine is directed to exit block 150 where before execution of the next instruction, a check is made for an external interrupt signal. If an external interrupt signal is present, the microroutine services it before execution of the next instruction.

Where bit 6 of the PSW is set in block 204, the A register is 40 set to X'0082 as shown in block 205, a PSW exchange is then completed in block 206. If the PSW at this point has bit 6 reset in block 208, then the microroutine enters block 210 where it exits at block 150A. Where PSW has bit 6 set the queue is checked for entries. If there are any entries, the microroutine 45 is directed to block 212. If there are no entries in the queue, the microroutine checks PSW bit zero in block 210. If this is set, it enters the wait state, block 214. If this is reset, the microroutine exits to phase zero block 150A.

There are two major advantages to this microroutine. The 50 first of these is related to the immediate interrupt which gives the user the ability to have up to 256 unique call locations, one per device and eliminates the need for identifying the device that is causing the interrupt. The second of these is derived from the interrupt service block mechanism in which data can 55 be transferred and pulses counted in a background mode without interrupting the currently running program. All of the microroutine is executed in between the execution of normal user instructions. It allows real time programs to be interrogated without interrupting the real time program. The external 60 attention can be simulated from a device that is not tied into this system at the time.

The system may be tested under program control by the 65 processor. Where such a simulated interrupt does not exist, any array of peripheral equipment attached to the computer would be required to generate signals in order to test the program. The simulate interrupt feature of the microroutine further allows the user to simulate an interrupt which will cause the program to take specific action. In specific, where the operator wishes the program to follow a certain path in the 70 program flow chart, a simulate interrupt signal may be sent to the microroutine which will allow the needed path to be followed.

There now follows a series of microprogram listings which 75 show location addresses and internal logic for the flow diagram description presented in FIGS. 5A-5D and discussed in the foregoing paragraphs.

What is claimed is:

1. A method for performing a microroutine built into a read only memory in accordance with a program being run on a processor having user's instructions in main memory to simulate external device interrupt signals comprising the steps of generating from said main memory a simulated external device interrupt signal, generating a device number defining said simulated interrupt signal, acknowledging within said read only memory containing said microroutine said simulated interrupt signals from said processor in accordance with said user's instructions, and performing programmed instructions of said microroutine after acknowledgement of said simulated interrupt signals without interrupting a program being run. 40
  2. A method for performing a microroutine built into a read only memory in accordance with a program being run on a processor having user's instructions in main memory and external devices which cause interrupt signals having discrete device numbers comprising the steps of acknowledging an interrupt signal within said read only memory and obtaining the device number of that interrupt signal for defining a particular service pointer, 45 50

fetching an interrupt service block function located in said main memory corresponding to said particular service pointer, and performing input-output service for said external devices in accordance with said interrupt service block function without interrupting said program that is being currently run.

3. The method of claim 1 in which there is provided the additional step of counting interrupt signals, and
decrementing said count after each interrupt signal, and
entering the currently running program after said interrupt signal is received.
  4. A processor system having a main memory to perform user's instructions and acknowledge interrupts from external devices having discrete device numbers in accordance with microroutines stored in a read only memory, comprising:
    - a. decode read only memory means for holding individual starting addresses each related to a particular one of said user's instruction microroutines,
    - b. an instruction register,
    - c. first decode instruction means for fetching a user's instruction from said main memory and placing it in said instruction register,
    - d. second decode instruction means for fetching the next user's instruction from said main memory, and
    - e. means for acknowledging said interrupts within said read only memory in accordance with a predetermined microroutine contained within said read only memory without interrupting a program being run within said main memory.
  5. The processor system of claim 4 wherein means for acknowledging said interrupts comprise:
    - a. an interrupt signal generated from said external devices, said interrupt signal to be acknowledged between successive user instructions, and;
    - b. a predetermined microroutine to perform functions specified by said external device and return to said user's instructions upon completion.
  6. The processor system of claim 4 in which there is provided:
    - a. a service pointer corresponding to said interrupt signal fetched from a service pointer table in said main memory,
    - b. an interrupt service block function located in said main memory to be fetched in accordance with the number of said service pointer, and;
    - c. means for performing input - output service for said interrupt means in accordance with said interrupt service block function without interrupting said program that is being currently run.
